VALVE BAG PACKING MACHINE

Webster Noyes Baker, Yeadon, Pa., assignor to
Bagpak, Inc., New York, N. Y., a corporation
of Delaware

Application August 25, 1933, Serial No. 636,664

11 Claims. (Cl. 226—48)

My present invention relates to an improvement in valve bag filling machines, whereby the filling of valve bags with pulverulent material is greatly expedited and the output of filled bags 5 materially increased.

In particular, my invention comprises means to improve the operation of valve bag filling machines in which the pulverulent material is dumped into a casing within which a continuous- 10 ly rotating impeller operates to force the material through a filling spout into a valve bag. In general, although my invention is illustrated and described in connection with a machine for packing valve bags, its salient features may be 15 incorporated in a machine so designed as to fill barrels or other containers through a filling spout inserted into a bunghole or opening in the container. For convenience, I refer to the machine as a valve bag filling machine, meaning thereby 20 a machine for packing pulverulent materials through a filling spout.

I have found that in the operation of previously built machines, a factor of delay is encountered in preventing the escape of dust into the packing 25 room. In packing coarse-grained materials, such as sugar, coffee or even cement, this factor is negligible, but in packing flour, cocoa, or the like, it becomes considerable since the impeller casing must be entirely emptied before the bag can 30 be removed from the spout. For instance, in packing cement eight seconds will ordinarily suffice to completely fill the bag, while the packing of a bag with hydrate of lime requires about twenty seconds. I have found that the charge is 35 almost completely packed in five seconds and only a few handfuls are forced out in the next few seconds. If the material is hydrate of lime, or the like, another ten or twelve seconds is required to remove the few ounces that remain in 40 the casing, since the operator could not remain in the room otherwise. This last bit of material would be discharged in a cloud through the unobstructed spout and render the atmosphere of the room extremely dangerous to life. This 45 amount of material does not detract from the standard weight of the filled container, and it is only to keep the atmosphere pure that an attempt is made to pack it into the container. Even so, no matter how long the bag is allowed 50 to remain on the spout, some of the material will escape. My invention is designed to allow the packing of the finest of materials in the same length of time that coarser materials require, and prevents the escape of any material into the room. 55 Another feature of my invention is that it may

be provided in each of a battery of machines, thereby increasing the output of such a battery.

Other features and advantages of my invention will be apparent from the following specification taken in connection with the accompanying 5 drawings.

Referring to the drawings wherein like numerals refer to like parts throughout:

Fig. 1 is a front elevation of a battery of two units, certain irrelevant parts being omitted; 10

Fig. 2 is a view partly in section of a portion of the battery structure;

Fig. 3 is a vertical section taken through the center of the first machine of the battery of Fig. 1 and looking toward the right; 15

Fig. 4 is a similar view showing a different phase of the operation of my invention.

Fig. 5 is a section of a modified form of my invention, and

Fig. 6 is an elevation thereof.

My invention is adaptable to a filling machine constructed according to the co-pending application of Arno Andreas, Ser. No. 570,331, filed October 22, 1931. In the aforesaid application the filling spout is provided with a rib which forms a space between the spout and the valve, which allows the escape of air from the bag being filled. Opposite this space is an opening in a suction conduit which draws off any escaping dust. It is not necessary that this construction be followed, 25 since my invention may be incorporated in any filling machine to which a suction conduit has been applied for the advantages fully set forth in the said application. Accordingly, I have illustrated a filling machine provided with a filling spout 10 adapted to receive a bag 11 and provided with a conduit 12 leading to a suction pump and settling tank, etc. I have found that the increased efficiency of my invention does not require the type of spout disclosed in the aforementioned application and therefore I provide the conduit 12 with an annular opening 13 around the base of spout 10, and an inlet 14 through the wall of spout 10 into the conduit 12 which leads upward. This construction is more efficient 30 in preventing escape of dust, allows the escape of air trapped with the material, and does not allow the loss of any appreciable portion of the charge through the suction conduit. The spout 10 extends substantially tangentially 35 from the bottom of an impeller casing 15 into which the material is dumped from a scale bucket or other charge-holding receptacle (not shown) through a hopper 16. A driven shaft 40 extends through the casing and has an im- 45

5 peller 18 mounted thereon. As illustrated, the impeller has three blades, but obviously any number of blades may be employed. As the charge is dumped into the impeller casing, the 10 blades, which are continuously driven at a high speed, force the material through the spout. Air, trapped with the material, escapes through the opening 14 and does not delay the filling of the bag. Any dust escaping through the valve is 15 drawn off through opening 13.

10 The last few ounces of material will remain in a cloud within the impeller casing and it is to remove this dust that my invention is utilized. A branch conduit 19 communicates with a valve 15 seat 20 in the casing, within which a valve 21 is placed. The valve is placed near the top of the casing, a position which was chosen as the result of actual tests showing it to be the best. A crank 22 attached to valve 21 is connected by 20 link 23 to a lever 24 pivoted on rod 25 and operated by handle 26. The opposite end of lever 24 is provided with a lateral arm 27 carrying an adjustable stop screw 28. Rod 25 is supported in lugs 29 on the casing between which is pivoted a clamp 30. The clamp is so formed that it 25 will hold a bag on spout 10 when it assumes a vertical position. The clamp is lifted by depression of handle 26.

30 The operation of my device is as follows. The operator clamps a bag on the spout, this action causing valve 21 to be closed through the connecting linkage (Fig. 3). The scale bucket is dumped by means of the usual operating lever to discharge the material into the impeller casing. The charge is packed in a few seconds, whereupon the operator depresses handle 26, allowing removal of the bag by raising clamp 30. This action also opens valve 21 simultaneously with the release of the bag. The blades of 40 the impeller repeatedly form substantially enclosed spaces to which valve 21 is the only outlet. The rapid rotation of the impeller blades creates a substantial pressure within the casing which corresponds to the pressure in a fan-type 45 blower. In the short time that the bag still remains on the spout after clamp 30 is released, the cloud of dust in the casing will be shot upward through conduit 19. Some of the dust will 50 tend to go directly outward through spout 10, but will be deflected upward through opening 14. This last I believe to be due to the increased suction through opening 14 caused by the forced draft effect of the air rushing through conduit 19. Regardless of the exact scientific theory 55 involved, I have found that even though the bag remains only momentarily on the spout after valve 21 is opened, substantially pure air only will be discharged into the room.

60 Although it is desirable to install the synchronized valve described above, it is obvious that an independently operated valve will give the same results. Accordingly, Figs. 5 and 6 illustrate a valve operated by a hand wheel 31 keyed to the hub 32 of valve 21. This type of device 65 is slower to operate but obviously as effective.

70 For certain types of material it has been found that the valve 21 need never be closed, and accordingly the conduit may terminate in a simple vent opening in the upper front quadrant of the casing. Obviously, a valve may be installed as illustrated, but since it remains open, the conduit becomes in effect a simple vent opening. In the machine illustrated wherein the hopper slopes inward on all sides at the upper rear quadrant 75 of the casing, it has been found that the best

operative position for such a vent opening is in the upper front quadrant, and that best results are attained when conduit 19 extends radially outward.

5 In Figs. 1 to 4 inclusive, I have illustrated the manner in which my valve may be installed in a battery of filling machines. Two machines or units A and B have a common impeller shaft 17 and a common rod 25. A sleeve 40 encloses rod 25, and lever 24 and handle 26 of unit A are fastened to sleeve 40. Dumping rod 41 for the scale bucket of unit B is attached to the other end of sleeve 40. A shorter sleeve 42 surrounds the intermediate portion of sleeve 40 and lever 24' and handle 26' of unit B are fastened to sleeve 42. Dumping rod 43 for the scale bucket of unit A is attached to the opposite end of sleeve 42.

10 This system of nested sleeves allows one operator to control the battery in the following manner. A bag is placed on unit A, handle 26 20 being at this time horizontal and valve 21 closed. The operator then depresses handle 26' which dumps the bucket in unit A through rod 43. The scale bucket is of the automatic type which automatically recloses and receives another precisely 25 weighed charge. A bag is now placed on unit B, and depression of handle 26 dumps the charge in this unit through rod 41. Clamp 30 and valve 21 are also opened by handle 26 and the filled 30 bag may be removed from unit A. The operations are now repeated, that is, an empty bag is placed on unit A and handle 26' is depressed to dump the bucket in A, release the bag on B and open valve 21; and so on.

35 It will be appreciated that although I have illustrated a two unit battery, I may employ my invention in a battery of any number of machines. The interconnected controls in a four unit battery would be substantially the same, with synchronism between the first and second 40 units, the second and third units, the third and fourth units, and the fourth and first units. Such a system of controls is shown in the co-pending application of Arno Andreas, Ser. No. 599,150, filed March 16, 1932. In any battery 45 the conduits 12, 12', etc., would be connected to a single suction pump and tank. The dumping rods 41, 43, etc. would be so connected to allow the following operation; a bag would be placed on the first unit, another bag placed on the second unit and the bucket dumped in the first 50 unit, and so on until a bag is placed on the fourth unit whereupon the first bag will be released. It would not involve more than the work of one skilled in the art to apply my invention to a four unit battery such as disclosed in the aforementioned application, Ser. No. 599,150. 55

While I have illustrated and described the preferred form of my invention, other modified forms will be apparent to those skilled in the art 60 and I do not intend to be limited except by the scope of the following claims which are to be broadly construed.

I claim:

1. In a valve bag filling machine having a filling spout, an impeller continuously rotating in a casing to which said spout communicates, and a suction conduit leading from said casing.
2. In a valve bag filling machine, a rotating impeller, an impeller casing, a filling spout leading from said casing, and a valved suction conduit communicating with said casing elsewhere than at said spout.
3. In a valve bag filling machine, an impeller, an impeller casing, a filling spout leading from

75

said casing, a suction conduit leading from said casing, a valve in said conduit, and means to operate said valve.

4. In a valve bag filling machine, an impeller, 5 an impeller casing, a filling spout leading from said casing, a suction conduit leading from said casing, a valve in said conduit, a clamp cooperating with said spout to hold a bag thereon, and means to release said clamp and open said 10 valve simultaneously.

5. In a valve bag filling machine, an impeller, an impeller casing, a filling spout leading from said casing, a suction conduit open to the atmosphere at the base of said spout and leading 15 upward, said spout having an opening into said conduit, and a valved conduit leading from said casing to said first conduit.

6. In a valve bag filling machine, an impeller, an impeller casing, a filling spout leading from 20 said casing, a suction conduit open to the atmosphere at the base of said spout and leading upward, said spout having an opening into said conduit, a second conduit leading from said casing to said first conduit, and a valve in said second conduit.

7. In a valve bag filling machine, an impeller, an impeller casing, a filling spout leading from 25 said casing, a suction conduit open to the atmosphere at the base of said spout and leading upward, said spout having an opening into said conduit, a second conduit leading from said casing to said first conduit, a valve in said second conduit, a clamp cooperating with said spout to hold a bag thereon, and means to operate said 30 clamp and said valve simultaneously.

8. In a battery of valve bag filling machines 35 each of which comprises an impeller, an impeller casing, a filling spout, a conduit leading from said casing, a valve in said conduit, a clamp to hold a bag on said spout and a charge-holding receptacle; means to release the clamp and open the valve of one machine simultaneously with

the dumping of the charge-holding receptacle of another machine.

9. In a battery of valve bag filling machines 5 each of which comprises an impeller continuously rotating in a casing, a filling spout leading from said casing, a suction conduit leading upward from said spout and having an opening surrounding the base of said spout, said spout having an opening into said conduit, a second conduit communicating with said first conduit 10 and the upper portion of said casing, a valve in said second conduit, a clamp to hold a container on said spout and a charge-holding receptacle; means to release the clamp and open the valve of one machine simultaneously with the dumping 15 of the charge-holding receptacle of another machine.

10. In a battery of valve bag filling machines 20 each of which comprises an impeller continuously rotating in a casing, a filling spout leading from said casing, a suction conduit leading upward from said spout and having an opening surrounding the base of said spout, said spout having an opening into said conduit, a second conduit communicating with said first conduit 25 and the upper portion of said casing, a valve in said second conduit, a clamp to hold a container on said spout and a charge-holding receptacle; interconnected means to release the clamp and open the valve of one machine simultaneously 30 with the dumping of the charge-holding receptacle of another machine, and a single operating handle for said means.

11. In a valve bag filling machine having a continuously rotating impeller, a casing for said 35 impeller having a feeding hopper located at the upper rear quadrant of said casing and a vent opening in the upper front quadrant of said casing, and a suction conduit leading radially outward from said opening.

WEBSTER NOYES BAKER.
